UNITED STATES PATENT OFFICE.

PIERRE ZENDER, OF LUXEMBURG-HOLLERICH, LUXEMBURG, ASSIGNOR TO PAUL WÜRTH & COMPAGNIE (SOCIETE EN COMMANDITE PAR ACTIONS), OF LUXEMBURG-HOLLERICH, GRAND DUCHY OF LUXEMBURG.

APPARATUS FOR CHARGING SHAFT-FURNACES.

1,393,480.

Specification of Letters Patent. Patented Oct. 11, 1921.

Application filed July 5, 1918. Serial No. 243,325.

To all whom it may concern:

Be it known that I, PIERRE ZENDER, a subject of the Grand Duchy of Luxemburg, residing at Rue Wedel, Luxemburg-Hollerich, in the Grand Duchy of Luxemburg, have invented certain new and useful Improvements in Apparatus for Charging Shaft-Furnaces, of which the following is a specification.

10 It is well known that in order to economize as far as possible motive power it is desirable to balance the ascending and the descending dead weights, and various attempts have been made to solve this problem in connection with the various types of charge elevating apparatus.

15 The object of the present invention is to deal with this problem in the particular case in which the material carried by the bucket or grab has to be moved successively along paths of different inclinations, for instance a vertical path followed by a horizontal path or by an inclined path. Such conditions occur for instance in connection with 20 the charging of high furnaces.

25 The invention may be said to consist essentially in coupling the cars from which the two charge receptacles are suspended during the vertical transport of the charges 30 in such a manner that the dead weight of the ascending charge vessel, bucket or grab is balanced by the dead weight of the descending vessel, and in uncoupling or disconnecting the two cars after the completion of the 35 hoisting operation so that the two cars may be moved independently during the subsequent horizontal transport.

35 The advantages of the invention are mainly the following, owing to the two cars 40 being coupled to form a single hoisting apparatus during the period of vertical transport, the dead weights of the two vessels containing the charge are fully balanced, which results in a saving of motor power 45 amounting to from 25% to 50%. Moreover as the empty and the full vessel are moved simultaneously the time required for the vertical transport may be reduced by 50%. During the vertical transport the elevating 50 motors of the cars are coupled and work simultaneously, therefore each motor will work as if under half load. Each of the motors should however be sufficiently powerful for raising the charge vessel and the

charge contained therein so that whenever 55 one of the cars requires to be repaired, the other car may be used for charging both furnaces.

It may also be mentioned that as the vessels may in this arrangement be elevated 60 within a vertical shaft, the danger of accidents to the attendants arising from the use of chutes or from accidental fall of the charge is considerably reduced. The cost of the whole charging plant is considerably 65 less than in other installations in which buckets or grabs are used. The accompanying drawings show three arrangements according to the invention. Figures 1 and 2 are a diagrammatic vertical section and a 70 plan of arrangement in which the two horizontal paths are in one line, the hoisting operation taking place in a plane passing through the vertical axes of the two high furnaces.

75 Figs. 3 and 4 are similar views of an arrangement in which the horizontal paths of the cars are at an angle, the vertical transport taking place outside the plane passing through the centers of the furnaces. 80

Figs. 5 and 6 illustrate an arrangement in which there is only one high furnace.

In Figs. 1 to 4 the cars are designated by the letters (a) and (b), the tracks along which the cars run are indicated by the letters (c), (d). (e) represents the ascending bucket or other receptacle containing the useful charge or load, (f) indicates the descending empty bucket, (g) are the ropes or cables, and (h) represents diagrammatically the coupling members of the drum shafts.

85 In the two arrangements shown in Figs. 1, 2 and 3, 4, respectively the operation is as follows: After the bucket (e) has been 90 charged at the bottom of the shaft or the usual charging point, the car (b) with its empty bucket (f) is coupled to the car (a) in such a manner that the two drum shafts of the cars are connected. The elevating 95 motors are then put into action and the vessel (e) is raised while the vessel (f) is simultaneously lowered. After the completion 100 of the vertical transport the motors are stopped and the cars are uncoupled. The 105 car (a) with the loaded vessel (e) may then be moved freely toward the discharge point along the track (c) by the motor provided

for this purpose, and at the same time the empty bucket (f) of the car (b) may be unhooked and replaced by the full bucket so that after the return of the car (a) the above described operation may be repeated in the opposite sense.

The invention may be also used in connection with a single high furnace but in such a case the dead weight of the charge vessel instead of being balanced by the weight of another charge vessel, is balanced by a counter weight which is coupled to the car in a similar manner as in the previous cases. Such an arrangement is shown in Figs. 5 and 6 in which the letters indicate similar parts as in the previous figures except that the letter (f) indicates a counterweight, while the letter (b) represents a stationary hoisting apparatus or drum.

20 I claim:—

1. The combination with two independently transportable hoisting drums, a charge vessel suspended from each drum, a separate driving shaft for each drum, and coupling members for connecting said shafts when the drums are brought together, whereby the weights of the vessels are balanced during the raising and lowering thereof.

2. An apparatus for charging shaft-

furnaces comprising a car, a charge vessel suspended from said car, means for hoisting and lowering said charge vessel mounted on said car, and means for coupling the hoisting apparatus of the car to a counter-weight during the hoisting operation and uncoupling the said hoisting apparatus from the counter-weight during the horizontal movement of the car.

3. A car for charging high furnaces comprising in combination a hoisting drum, a charge vessel suspended from said hoisting drum, means for operating the drum, and means for coupling and uncoupling the shaft of the drum to the shaft of another drum carrying a counter-weight.

4. The combination with two shaft furnaces, of a car for each furnace, movable to and from the latter, a hoisting drum on each car, a charging vessel suspended from each drum, a driving shaft for each drum, and means for coupling the drum shafts together during the operation of the drums, whereby the weights of the vessels are balanced during the raising and lowering thereof.

PIERRE ZENDER.
